US00D617289S

(12) **United States Design Patent**
Panaccione et al.

(10) **Patent No.:** **US D617,289 S**
(45) **Date of Patent:** **** *Jun. 8, 2010**

(54) **LED PACKAGE**

(75) Inventors: **Paul Panaccione**, Newburyport, MA (US); **Christian Hoepfner**, North Andover, MA (US); **Georgia Chmielewski**, Plaistow, NH (US)

(73) Assignee: **Luminus Devices, Inc.**, Billerica, MA (US)

(**) Term: **14 Years**

(21) Appl. No.: **29/285,460**

(22) Filed: **Mar. 29, 2007**

(51) **LOC (9) Cl.** **13-03**

(52) **U.S. Cl.** **D13/180**

(58) **Field of Classification Search** **D13/180, D13/182; D26/2; 257/79, 80, 81, 88, 89, 257/95, 98, 99, 100; 313/483, 498, 500; 362/555, 800; 174/254, 255**

See application file for complete search history.

(57) **CLAIM**

The ornamental design for a LED package, as shown and described.

DESCRIPTION

FIG. 1 is a side, top perspective view of the LED package showing our new design;

FIG. 2 is a top plan view thereof;

FIG. 3 is a right side view thereof;

FIG. 4 is a left side view thereof;

FIG. 5 is a front view thereof; and,

FIG. 6 is a rear view thereof.

The broken line showing of the environment is for illustrative purposes only and forms no part of the claimed design.
